Inventor:
Oscar Junghren,
by *Alfred S. Lunt*
His Attorney.

UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ROTOR FOR ELASTIC-FLUID TURBINES.

Application filed April 20, 1923. Serial No. 633,340.

To all whom it may concern:

Be it known that I, OSCAR JUNGGREN, a citizen of the United States, residing at Schenectady, county of Schenectady, State 5 of New York, have invented certain new and useful Improvements in Rotors for Elastic-Fluid Turbines, of which the following is a specification.

This invention relates to rotors for elastic-10 fluid turbines and an improved method of constructing the same, the object being to provide a rotor which may be built up of any desired number of simple, easily manufactured sections to form a rugged, light-15 weight, unitary structure in which said sections form a hollow shaft.

To this end, the present invention, which is herein described and illustrated in its application to rotors for small steam turbines, provides a rotor having a hollow shaft 20 formed of a multiplicity of tubular-hubbed stage wheels aligned one upon the other and joined together by fusion of metal at the engaging surfaces. This gives a rotor structure which is as light as and somewhat more 25 flexible than that of the common hollow shaft type with the wheels carried on said shaft.

This construction readily lends itself to 30 assembling into a rotor as many wheels as may be required to provide the proper number of stages for any installation, to extract the energy from the elastic fluid at the pressure and temperature supplied or 35 available. Hence it will be seen that in connection with small steam turbines which are built to meet a large variety of operating conditions upon which to a great extent the number of wheels used is dependent, the 40 present invention provides a convenient and efficient means for building up a correspondingly great variety of rotors to meet these conditions economically, from a standard stock of wheels of few sizes.

45 For a consideration of what is considered to be novel and the invention, attention is directed to the following description, claims appended thereto and the accompanying drawing.

50 In the drawing, Fig. 1 is a side view,

partly in section, of one embodiment of the invention and Fig. 2 is a similar view of a modification.

Referring particularly to Fig. 1, 3 indicates a number of turbine bucket wheels 55 arranged to form a series of ordinary stages. These wheels are simple disks carrying buckets, indicated at 4, at their peripheries and are formed with hollow projecting hubs 5 pressed and drawn out from their centers. 60

The wheels are centered with respect to a common axis and held in proper spaced axial relation by a shouldered portion of each hub being pressed into a corresponding counterbore in the next succeeding wheel 65 hub as indicated at 6, such that when fitted together they form a unitary rotor structure with what is substantially a hollow shaft 7. Since this hollow shaft is formed by the wheels themselves, it is automatically ex- 70 tended as more wheels are added and collateral with this desirable feature is the light weight and economy of material accruing from the hollow shaft construction. 75

To provide a set of bearings for the assembled rotor, a shouldered hub is forced into either end of the hollow bore as indicated at 8. These hubs are provided with a suitable bearing surface as indicated at 9 and a tapered end portion 10, to which last 80 mentioned portion any suitable form of driving connection, for example, a shaft coupling may be fitted.

The portions of the shouldered hubs 8 which extend within the wheel bore are 85 axially counterbored as indicated at 11 to permit the hubs to expand and contract with the wheels as they are subjected to changing temperatures, without setting up stresses 90 which would tend to cause separation of 95 the wheels from the hubs.

It will be noted that the bearing hubs 8, as well as the hubs 5 of the successive stage wheels 3, are fitted with the usual packing rings indicated at 12, being well adapted 95 to carry these rings without any special fittings other than circumferential grooves machined or pressed into said hubs.

When the rotor parts are ready for final 100 assembly, the required number of wheels 3

are arranged in the desired order between the bearing hubs 8 and are then drawn together into the assembled unit as shown in the drawing. They are held in this assembled relation firmly bound together by a tie rod 13 passed through the center of the structure and threaded at either end to receive clamping nuts, indicated at 14, which are drawn up firmly, against the outer ends 5 of the bearing hubs. To accommodate the rod 13 and to properly locate it at the center of the structure, the bearing hubs 8 are provided with axial passages as indicated at 15. This method of clamping the parts into a 10 firm assembly is used only by way of example as being that which is now considered to be the most desirable, although it will be understood that means other than that employing the rod 13 may be used without departing from the spirit of the invention. 15 With the rotor assembled and firmly bound together, the interengaging and adjoining surfaces between the individual parts, namely the end hubs, packing rings 20 and wheels, are united into a permanently bonded unitary structure by fusion of metal; for example by welding or forging the parts together by any suitable method. The clamping nuts 14 and the tie rod 13 may 25 then be removed. The finished rotor is then ready for use.

Referring to Fig. 2, a modification is shown to which the same reference numerals as used in connections with Fig. 1 have been 30 applied with the exponent "a" added.

The differentiating feature of this modification lies in the type of wheel hub employed to form the hollow shaft. In forming the wheel hubs by pressing and drawing out the centers of the wheel blanks, a sufficient quantity of material may not be obtained to provide long shouldered hubs, for example like those of Fig. 1. Hence as a 35 substitute means to provide sufficient bonding surface for uniting the hub of one wheel to the next, a flange 16 is formed at the end of a short wheel hub 5^a. This flange is provided on its face with a short annular shoulder which is forced into a corresponding 40 shallow counterbore in the next wheel as indicated at 6^a. The shoulder and counterbore 6^a serve in this modification merely as means for centering each wheel with respect to the next along a common 45 axis of rotation.

The remainder of this modification and its assembly do not differ from the showing in Fig. 1 as described and for this reason further description is believed unnecessary.

In either Fig. 1 or Fig. 2 the wheel hubs shown may, if the material used does not admit of pressing and drawing out, be formed by casting integrally with the wheel, the form and resulting assembly being the same as before described.

From the foregoing description in connection with Figs. 1 and 2, which are only by way of example, it will be seen that in accordance with the present invention, a rotor may be built up of any desired number of interengaging parts of simple, easily manufactured design and formed into a unitary structure having an automatically extensible hollow shaft, without the use of the commonly employed separate hollow 75 shaft of fixed length. This permits of great flexibility in construction, especially in connection with rotors for small elastic-fluid turbines, as these may be built up of standard wheels of few sizes to meet the 80 varying requirements as to steam and other operating conditions in any case. The problem of meeting these conditions is, through the present invention, reduced practically to that of deciding how many wheels 85 shall be stacked one on the other to form the required rotor, the wheel sizes being standardized and the shaft length being automatically taken care of.

It will be understood that the present invention is not necessarily limited to turbine rotors but may be applied in other fields and may be carried out by other means.

What I claim as new and desire to secure by Letters Patent of the United States, is:

1. A rotor for an elastic fluid turbine or the like comprising a hollow shaft and a plurality of wheel members mounted thereon, the wheel members being provided with integral tubular hubs which are arranged in coaxially aligned engagement with each other and united to form said hollow shaft. 100

2. A rotor for an elastic fluid turbine or the like comprising a plurality of separate wheel members, each of which is provided with a projecting tubular hub integral therewith, the hubs telescoping one within the other and being united to provide a continuous hollow shaft for the rotor. 105

3. A rotor for an elastic fluid turbine or the like comprising a plurality of wheel members provided with integral hollow hubs projecting axially from their centers, said hubs nesting one within the other whereby they serve to center said wheel members relatively to each other and to provide a hollow shaft for the rotor, bearing members for the rotor secured in the ends of the hollow shaft, and means for uniting the assembled members into a unitary structure. 115

4. A rotor for an elastic fluid turbine or the like comprising a plurality of wheel members each provided with a central axially-extending integral hub, the hubs serving to center and space said wheel members relatively to each other and being united by fused metal, and end plugs which provide bearings for the rotor. 125

5. A rotor for an elastic fluid turbine or the like comprising a plurality of wheel 130

members provided with integral hollow hubs projecting axially from their centers, said hubs nesting one within the other whereby they serve to center said wheel members relatively to each other and to provide a hollow shaft for the rotor, means formed on the hubs for spacing said wheel members

relatively to each other, bearing members for the rotor secured in the ends of the hollow shaft, and means for uniting the assembled members into a unitary structure. 10

In witness whereof, I have hereunto set my hand this 19th day of April, 1923.

OSCAR JUNGGREN.
